UNITED STATES PATENT OFFICE.

FREDERICK S. CHASE, OF WATERBURY, CONNECTICUT, ASSIGNOR TO THE
WATERBURY MANUFACTURING COMPANY, OF SAME PLACE.

DESIGN FOR AN OIL-CAN.

SPECIFICATION forming part of Design No. 25,323, dated March 31, 1896.

Application filed February 17, 1896. Serial No. 579,655. Term of patent 7 years.

To all whom it may concern:

Be it known that I, FREDERICK S. CHASE, of Waterbury, in the county of New Haven and State of Connecticut, have invented a new Design for an Oil-Can; and I do hereby declare the following, when taken in connection with the accompanying drawings and the letters of reference marked thereon, to be a full, clear, and exact description of the same, and which said drawings constitute part of this specification, and represent, in—

Figure 1, a view in side elevation of my newly-designed oil-can; Fig. 2, a plan view of the body of the can with the spout and cap removed.

This invention relates to a design for oil-cans; and it consists in the configuration as herein described, and shown in the accompanying illustration.

As herein shown, my newly-designed oil-can consists of a bell-shaped body A, having lon-

gitudinal flutes or corrugations A' placed close together and encircling it. These corrugations terminate at their lower ends in a plain fillet or base A², and at their upper ends in a neck A³, surmounted by a flange A⁴, and receiving a tapering spout A⁵ inclosed by a cylindrical cap A⁶. 25

The essential feature of my newly-designed oil-can is its bell-shaped and fluted or corrugated body. 30

I claim—

The design for an oil-can as herein shown and described.

In testimony whereof I have signed this 35 specification in the presence of two subscribing witnesses.

FREDERICK S. CHASE.
